7 Claims. (Cl. 179—171)

It is known that if the electrodes are mounted in a suitable manner considerable gains are obtainable with the gaseous discharge type of amplifier tubes. One well known electrode arrangement in gaseous discharge amplifiers, for instance, is based upon the principle of utilizing for the electron source a constant and quiet direct current glow discharge produced between two electrodes. In this scheme the electrons are, as it were, extracted from the glow discharge gap in the form of a dark or silent discharge by the action of an electric field of an amplifier anode. The potentials of the grid located between the glow discharge gap and the amplifier anode or plate are then able to control the electronic current flowing to the amplifier anode. However, one disturbing effect in all of these schemes known in the prior art is the production of relatively strong grid currents. While in modern amplifier art a limitation of the grid currents to not over 10^{-6} milliamperes is imperative, glow discharge or gaseous conduction amplifier tubes of the kind just referred to exhibit the presence of considerably larger grid currents.

Now, in order to minimize these grid currents it has previously been suggested to so dispose the anode of the glow discharge gap that the amplifier electrodes, especially the grid, will be shielded thereby from fast electrons. Nevertheless, troublesome grid currents have been noted in the arrangements disclosed in the earlier art, and these are ascribable to ionization of the gas caused by ionic impacts. Now, the present invention discloses ways and means to eliminate the troublesome effect of these currents. According to this invention, the gaseous conduction amplifier tube, contradistinct to what has been known before, is provided not with a single grid, but rather two or three grids mounted in the space between the amplifier anode and the glow-discharge gap. By the judicious choice of the biasing potentials to be applied to the auxiliary or supplemental grid or grids it is possible to preclude disturbing charges or currents from the control grid proper.

If the auxiliary or supplementary grid, as will be noted, is given a biasing potential which is negative relative to the control grid, this auxiliary grid acts as a means whereby the ions caused by impact ionization of the disturbing gas admixtures are extracted or absorbed, and the result is that the alternating potentials applied to the control grid and to be amplified will no longer be influenced by this grid cur-

rent. Such ion absorbing action of the auxiliary grid will be particularly favorable when the inter-electrode distances and the gas pressure are so chosen that only a few mean free paths of the electrons are feasible so that practically no impact ionization will occur in the amplifier space. In this arrangement the effect of the ion-collecting grid would be confined to the absorption of ions which are produced by the action of electrons in the path between the glow discharge gap and the amplifier electrodes.

However, whenever the gas filling of such a glow discharge amplifier tube is extremely pure, the disturbance residing in ionic currents to the grid as above described will no longer arise, though, on the other hand it becomes noticeable that the slope of the characteristic of such an amplifier is greatly impaired compared with what it is in the presence of slight admixtures of extraneous gases. Also where extremely pure gases are concerned, the provision of a second grid offers substantial advantages. By choosing a suitable potential preferably slightly positive for the second grid it is possible by virtue of its presence to avoid the space-charge due to the electrons, in other words, to strictly define the distance between cathode and anode. In this way conditions are made so that even gaseous conduction amplifiers containing pure gases having characteristics with slopes of a useful order of magnitude are obtainable.

For purposes of illustration the accompanying drawing shows diagrammatically one embodiment of the invention. The tube shown in the drawing comprises a sealed envelope 1 containing gas at the proper pressure and having an anode 2 and a glow discharge gap with two electrodes 3 so spaced that a glow discharge can be maintained between them by a suitable source of current, such as a battery 4. The anode is maintained at the proper positive potential relative to the electrodes of the glow discharge gap by a battery 5 with its negative pole connected to one of the glow discharge gap electrodes 3 and its positive pole connected through a load, such as the transformer 6, to the anode 2.

The alternating voltages from any suitable source may be impressed thru a transformer 7 on a control grid 8 adjacent the anode, and an auxiliary grid 9 is mounted between the control grid and the glow discharge gap. The potential of the auxiliary grid is maintained constant by suitable means, such as a biasing battery 10 connected to the auxiliary grid 9 and prefer-

ably to an electrode of the glow discharge gap. In the drawing the auxiliary grid 9 is shown connected to the negative pole of the biasing battery, so that the grid is negative with respect to the glow discharge gap electrodes and also to the control grid 8 connected to one of these electrodes, but the connection may be reversed when it is desired to make the auxiliary grid a space charge grid and maintain it positive as may be desirable in some cases, for example, where the gas in the envelope 1 is very pure.

I claim:

1. A gaseous conduction amplifier comprising a sealed envelope containing a gaseous atmosphere and enclosing an electron source comprising a pair of gaseous discharge electrons spaced to form a gap in which a discharge may be maintained, a plate electrode, a control grid, and an auxiliary grid between said control grid and said electron source positively biased with respect to both of said discharge electrodes.

2. A gaseous conduction amplifier comprising a sealed envelope containing a gaseous atmosphere, a pair of electrodes mounted in said envelope to form a glow discharge gap, a plate, a control grid, an auxiliary grid between said discharge gap and said control grid and biased to enable said auxiliary grid to trap ions appearing in said envelope, the interelectrode distances and the gas pressure being so related that impact ionization in the space between said grids and said plate is substantially absent.

3. A gaseous conduction amplifier comprising a sealed envelope containing a gaseous atmosphere and enclosing an electron source comprising a pair of electrodes spaced to form a gap in which a discharge may be maintained, a plate electrode, a control grid, and a space charge grid between said control grid and said electron source, the spacing between said anode and said control grid and the pressure of said atmosphere being so related that impact ionization in the space between them is substantially absent.

4. A gaseous conduction amplifier comprising a sealed envelope containing a gaseous atmosphere and enclosing an electron source comprising a pair of gaseous discharge electrodes spaced to form a gap in which a discharge may be maintained, a plate electrode, a control grid adjacent said anode, and a space charge grid ad-

jacent said electron source and positively biased with reference to both of said discharge electrodes, and means for supplying a constant positive potential to said space charge grid.

5. A gaseous conduction amplifier comprising a sealed envelope containing a gaseous atmosphere and enclosing an electron source comprising a pair of electrodes mounted in said envelope to form a discharge gap, a plate, a pair of grids between said discharge gap and said plate, the grid adjacent the anode being directly connected through an impedance to one of the discharge electrodes, and the grid adjacent the discharge gap being directly connected through a source of biasing potential to the other discharge electrode.

6. A gaseous conduction discharge device comprising a sealed envelope containing a gas at low pressure and enclosing a pair of electrodes spaced to form a gap in which a gaseous conduction discharge may be maintained, a plate, a control grid adjacent said plate, a transformer secondary connected to one of said electrodes and to said control grid, an auxiliary grid between said electrodes and said control grid, a source of constant potential connected to the other of said electrodes and to said auxiliary grid, a source of higher potential connected to said other electrode and to said plate, a source of potential connected to both said electrodes to maintain a discharge between them, and means for impressing a variable potential on said transformer secondary.

7. A gaseous conduction discharge device comprising a sealed envelope containing a gaseous atmosphere, a pair of electrodes disposed in spaced parallel relation mounted within said envelope and forming a glow discharge gap, a source of potential connected between said discharge gap electrodes, a plate, a source of potential connected between the first mentioned source and the plate, a plurality of grids extending in planes at right angles to the discharge electrodes and interposed between said discharge gap and said plate, and means for impressing a variable potential on one of said grids, and means for impressing a constant potential on the other of said grids.
